UNITED STATES PATENT OFFICE.

WILHELM ALBERT CARL BLANKENBURG, OF AMSTERDAM, NETHERLANDS.

MACHINE WITH ROTARY AND SELF-CONTROLLING CYLINDERS.

1,328,261.

Specification of Letters Patent.

Patented Jan. 20, 1920.

Application filed July 2, 1914. Serial No. 848,626.

To all whom it may concern:

Be it known that I, WILHELM ALBERT CARL BLANKENBURG, a subject of the Queen of the Netherlands, and resident of Nieuwe 5 Looierstraat 9, Amsterdam, Netherlands, have invented new and useful Machines with Rotary and Self-Controlling Cylinders, of which the following is a specification.

The present invention relates to machines 10 with rotary and self-controlling cylinders. The individual cylinders are preferably disposed within a common casing. The essential feature of the present invention consists in the special construction of the abutment, on which the revolving cylinders slide 15 with their controlling surfaces. The cylinders are generally vaulted within at their upper end in form of a hemisphere. It is known to make with such cylinders the two bearing surfaces likewise of a hemispherical 20 shape. The characteristic feature of the present invention, consists in that these bearing surfaces have the shape of an inverted cone. Thereby a wide space is obtained between the inside of the cylinder end and the 25 bearing surface, which may be utilized for improving the cooling and also the admission and the discharge of the cooling medium. A further feature of the present invention consists in that a second passage is 30 provided opposite to the passage in the top end of the cylinder controlling the admission and the exhaust, so that the cylinder is fully counterbalanced. A further improvement 35 of the rotary valve cylinder consists in that the cylinder head, which in this case is completely separate from the casing, is provided with a ring-shaped bearing which is bolted to the cylinder head and carries 40 the cylinder. It is thereby rendered possible to pack the cylinder so that it may turn easily, while the cylinder is still outside of the engine and has not yet been assembled. This allows of a very convenient 45 assembling. In this case, indeed, the controlling passages must form the communication and take up all stresses occurring. It also caused some difficulty in introducing the 50 sparking plug, as a packing was there required. The arrangement may be therefore so modified, that the upper end of the cylinder is not made in form of a closed vault, but left open at the top, a circular piece being cut out from the top of the vault. To

this circular opening connects a tube, which 55 is constricted in a neck-like fashion, on which tube finally the valve face extending in shape of a funnel toward the outside is secured. The passages for the gases are disposed laterally to the constricted neck. 60 Into this neck engages a suitable plug-shaped lug cast in one piece with the stationary abutment lid, so that its lower surface completes the interrupted curvature of the vault in the cylinder head. This plug-shaped lug contains cooling spaces and the 65 sparking plug and is packed at the sides against the neck of the cylinder. The great advantage of this arrangement consists in that the valve face is discontinued at those 70 points, where the greatest friction is caused, namely in the center, which besides is useless for the control. Furthermore a solid and secure connection between the valve face 75 and the cylinder is provided.

In the accompanying drawings several embodiments of the present invention are exemplified. Figure 1 is a sectional side view of one embodiment. Fig. 2 is a top view of the packing surface of the revolving cylinder. Fig. 3 is a bottom view of the corresponding surface of the cylinder head. Fig. 4 is another embodiment, shown partly in section. Fig. 5 is a bottom view of the joint cylinder head. Fig. 6 is a top view of 80 the packing surface of one cylinder. Figs. 7, 8, 9 illustrate a third embodiment of the present invention seen from in front, partly in section, from the side in section on the line A—A and B—B respectively, in Fig. 7. 90 Figs. 10 and 11 show the packing ring of the revolving cylinder in side view and section respectively. Fig. 12 illustrates the special arrangement of the cylinder head in section seen from one side. Fig. 13 is a top 95 view of the valve face. Fig. 14 is the casting of the cylinder removed.

The first embodiment is illustrated in Fig. 1. The closed end of the cylinder 1 is made on the inside of a hemi-spherical 100 shape. The bearing surfaces 2 and 2^a however are of a conical shape, which is so disposed that the point of the cone is inclined toward the apex of the cavity of the cylinder. This center of the bearing surfaces is, in the present embodiment, formed by a hollow shaft 3 which is guided in a sleeve-like extension 4' of the cylinder head 105

4 and runs at the upper end in a ball bearing. This hollow shaft may serve to receive the sparking plug 5. This affords the advantage, that the ignition occurs at the most favorable point and that there is no danger of the sparking plug being soiled with oil. The controlling faces are made as follows:

In the double head of the cylinder a passage 6 is provided, which has the section of a sector, having in the present embodiment an area of $\frac{1}{4}$ of the surface of the cylinder head. This passage serves as admission and exhaust duct for the gases entering into and escaping from the cylinder. Opposite to the passage 6 three openings (Fig. 3) are provided in the cylinder head, namely the admission duct 7 for the gases coming from the carburetor, the exhaust duct 8 for the exhaust gases and the opening 9 for a second sparking plug or the compression cock. It is thus obvious that when the cylinder revolves it will in succession bring its passage 6 into register with one of the openings 7, 9, and 8 and thereby, in succession bring the cylinder chamber into communication with the gas supply, the ignition and the exhaust pipe. A suitable oil-supply is provided at the center of the cylinder-head journal.

The cylinders are revolved by the driving gear which transmits the movement of the piston to the main shaft. This transmission is performed for the purpose of obtaining a four-cycle, or for running the engine on the four-cycle principle at half speed by the toothed flange 10. An adjustable ball bearing bears from below against the toothed flange 10 and holds the cylinder pressed against its journal in the cylinder head during the suction period, whereas during the other three strokes the cylinder is automatically pressed down on its journal. Between the cylinder and the casing a packing 11 is provided.

The outside of the cylinder and the top side of the cylinder head are closely covered with radiator webs 12 which also fill up the whole space between the vaulted cylinder head and the bearing surface.

A second embodiment is illustrated in Figs. 4-6. Here the arrangement of several cylinders within one joint casing is shown.

In Fig. 4 four cylinders are disposed next to each other in a joint casing. The closed ends 13 of the cylinders are also here of a hemi-spherical shape on the insides and have passages 6. The upper end of the top of each of the cylinders is provided with a bearing surface having the shape of a hollow cone 4, the point of which lies in the central axis of and is inclined toward the cylinder chamber. For all four cylinders a common abutment part 14 is provided, in which the admission passages 7 and the ex-

haust passages 8 are disposed. This abutment part is made with a corresponding conical bearing surface. The space between the inner side of the cylinder head and the conical surface is closely covered with radiator webs, the same as also the whole outside of the cylinder is covered with such webs. Also the outside of the abutment part may be provided with radiator webs. With this embodiment the arrangement is such, that instead of one passage 6 in the cylinder head two such passages are symmetrically arranged to the central axis. This affords the advantage of preventing the cylinder from heating on one side. Owing to the arrangement of these two passages, furthermore, the speed of the cylinder is reduced to one quarter of the speed of the crank shaft, so that in consequence of the lower speed of the cylinder the tendency toward heating is reduced.

The cylinders 1 are journaled in the following manner in the engine casing. Between the two bearings 15 and 16 is arranged the toothed flange 17. The bearing 16 is threaded and adjustable. It bears with its upper surface against the flange 18 and holds the two conical bearing surfaces at the top pressed against each other. The cylinders are driven from the crank shaft 19 in such a manner, that a pair of bevel gears 26 rotates an auxiliary controlling shaft, which by means of its pinion 21 drives the toothed flanges 17 of the cylinders (Fig. 4). The crankshaft drives the piston rods 22. The casting 14 is supported by six vertical brackets 23, which terminate at the top in a continuous flange 24. The cylinders are covered all around with webs 12.

The third embodiment is illustrated in Figs. 7 to 11.

With this embodiment a ring 25 is provided, which is secured to the cylinder head and engages over the flange of the face 2 at the top end of the cylinder in such a manner, that the cylinder can revolve freely therein. In this embodiment each cylinder has a separate head 14^a, 14^b, 14^c, 14^d, with which it may be assembled before it is fitted into the joint casing.

The arrangement of the cylinders according to this embodiment is chiefly intended for long stroke engines, in which the ratio between bore and stroke is at the least 1:2. For this purpose the cylinder is transversely divided, so that not the whole, but only a part of the cylinder, namely that part in which the combustion takes place, revolves while the other part remains stationary and is, in known manner, provided with an outwardly flaring lower end for allowing a free play of the connecting rod. The revolving part of the cylinder is, in consequence of such arrangement, very light, and this part is very uniformly heated. This

revolving part 1^a of the cylinder is journaled in the stationary part 1^b. It is superfluous to employ a special journal for the revolving part. The lubrication of the cylinder walls and of the journals is in close relation and may be effected in such a manner, that the surplus oil from the cylinder wall passes through passages in the revolving cylinder and then lubricates the cylinder journal. 5 The driving wheel is journaled either in a plain or a ball bearing in such a manner, that the wheel 26 fits with a recess on a rest 27 in the stationary cylinder part 1^b. The watertight joint between the revolving cylinder and the stationary water jacket is obtained by the provision of a packing 28 and 10 29 at the top and bottom respectively, between which a metallic ring 30 is disposed, which is provided with grooves and water holes. If, therefore, the upper packing should let water pass through, it will be received by the ring 30 and may be let off by means of the tap 31, the lower packing preventing such water penetrating into the engine casing. The tap 31 therefore serves to 15 control the packings from outside whether they are watertight or not and may be used to drain off any water which happens to leak into the packing. The spring 32 is disposed in such a manner, that it is not, as usual, outside of the water chamber, but within the latter. It is made of round or flat bronze wire, so that it will resist the action of the water. Its effect is such that it presses together the bearing surfaces of the cylinder 20 valve with the one end, and with the other end holds the metallic packings tightly pressed together. If the spring is made of flat wire, it will besides essentially promote the circulation of the water in accordance with the well known action of liquids. The cylinders are driven in the following manner: The sprocket 33 drives the sprocket 34 of even diameter on the controlling shaft at the 25 same speed as the crank shaft. The controlling shaft drives the cylinders by means of worm gears 35 at a rate of 1:4. The cylinders thus revolve at one quarter of the speed of the crank shaft. The engine is assembled in the following manner: The cylinder head 14^a is bolted to the ring 25, so 30 that the cylinder 1^a can revolve freely. Then the cylinder part 1^b is fitted into the casing 36. On the part 1^b is placed the wheel 26 fitting on the rest 27. Then the water jacket 37, containing the packings 28 and 29 is placed in position and bolted to casing 36. Now the spring 32 is laid around the part 1^a and these parts are let into the water jacket 37. 35 The part 1^a has lugs, which engage the cylinder with the wheel and thereby revolve it. After the cylinder has been fitted the head 14^a is bolted to the water jacket and the engine is ready for working. In Fig. 7, I show in dotted lines how a cylinder with its

attached head may be vertically removed from or placed in position in the water-jacket 37.

In the embodiment according to Figs. 11-13 the upper vault 13 is cut away in the center in a circular fashion. This opening is extended in form of a constricted neck 38, the upper end of which carries the funnel-shaped valve face 2. The passages 6^a and 6^b opening in this face extend downward at 75 both sides of the neck until they enter into the engine cylinder. The bearing face of the valve seat is mounted revolubly against an abutment lid 14, which is rigidly secured to the casing 37. It contains extensions 7^a, 7^b 80 of the passages 6^a, 6^b and besides a number of cooling water chambers 39. It also carries the conical abutment surfaces 2^b on which the valve face is guided. According to the present invention this lid has a concentric casting 40, which in form of a plug extends downward into the neck 38 and is fitted well into the latter. The joint between these two parts may, for example, be sealed by means of an elastic piston ring 41. 85 The lower end of the plug has a spherical recess, so that it completes the cut away hemi-sphere of the top end of the cylinder. At a suitable place, preferably in the center of the plug the sparking plug 5 is disposed. The lubricating of the joint surface between the plug casting 40 of the lid and the neck 38 of the cylinder is automatic by the oil dripping from the funnel-shaped face of the valve seat. 90

100

I claim:

1. In a combustion engine of the class described, a revolving and self-controlling cylinder having one end closed with its interior hemispherically vaulted with a central 105 circular opening and provided with a restricted tube-shaped collar having its outer surface formed with a valve-face and one or more ports opening upon said valve-face, a valve-seat having a plug-like projection fitting said circular opening of the cylinder end and serving to complete the head of said cylinder. 110

2. In a combustion engine of the class described, a revolving and self-controlling cylinder having one end closed with its interior vaulted with a central circular opening and provided with a depressed annular valve-face and one or more ports opening upon said valve-face, a funnel-shaped valve seat 115 having a central constricted neck fitting the circular opening in the end of said cylinder, the end of said neck having a recess adapted to complete the vault of the head of the cylinder. 120

3. In a combustion engine of the class described, a revolving and self-controlling cylinder having one end closed and provided upon its exterior with a valve-surface, one or more ports extending through said end and 130

125

opening upon said valve-surface, the said end of the cylinder being provided with an external flange, a correspondingly shaped seat for said valve-surface provided with ports coöperating with said port or ports on the valve-surface, and a ring-shaped bearing engaged by the flange on said cylinder.

4. In a combustion engine of the class described, a revolving and self-controlling cylinder having one end closed and provided upon its exterior with a valve-surface, one or more ports extending through said end and opening upon said valve-surface, a correspondingly shaped seat for said valve-surface provided with ports coöperating with said port or ports on the valve surface, a casing and a water-jacket space between said cylinder and casing, packings at the lower end of said cylinder, a fixed part on said cylinder, and a spring interposed between said fixed part on the cylinder and said packings, whereby the spring acts to keep the cylinder-valve pressed to its seat and the packings pressed together.

5. In a combustion engine of the class described, a revolving and self-controlling cylinder having one end closed and provided upon its exterior with a valve-surface, one or more ports extending through said end and opening upon said valve-surface, a correspondingly shaped seat for said valve-surface provided with ports coöperating with said port or ports on the valve surface, the said cylinder being transversely divided into two sections the lower one of which is stationary while the upper one in which the

combustion takes place is revolvably journaled on the lower section thereby reducing the weight of the revolvable part.

6. In a combustion engine of the class described, a revolving and self-controlling cylinder transversely divided into two sections, the lower section being stationary and the upper one in which the combustion takes place revolvably journaled on the lower section, and a toothed gear secured to said revolvable section and journaled on a fixed part on said lower section thereby reducing the weight of the revolvable part.

7. In a combustion engine of the class described, a revolving and self-controlling cylinder having one end closed and provided upon its exterior with a valve-surface, one or more ports extending through said end and opening upon said valve-surface, a correspondingly shaped seat for said valve-surface provided with ports coöperating with said port or ports of said valve surface, a series of packing members for said cylinder, a perforated ring interposed between said members, and a tap connected with said ring for collecting and draining the water leaking through the upper packing.

In testimony, that I claim the foregoing as my invention, I have signed my name in presence of two witnesses, this twentieth day of June 1914.

WILHELM ALBERT CARL BLANKENBURG.
